BOLT ACTION FIREARM WITH AUTOMATIC SAFETY MECHANISM ENGAGEABLE BY BOLT HANDLE

Oliver M. Knodle, Jr., Hampden, Mass., assignor to Savage Arms Corporation, Westfield, Mass., a corporation of Delaware

Filed Oct. 2, 1961, Ser. No. 142,162
7 Claims. (Cl. 42—70)

This invention relates to bolt action firearms and more particularly to firing safety mechanisms for small arms.

As is well known, the function of a safety mechanism for firearms is to prevent inadvertent firing of the weapon. Any safety which must be intentionally actuated or placed "on" by the shooter leaves a great deal to be desired because it requires an additional human action other than that required to load and fire the weapon.

This invention relates to a type of safety known as an "automatic safety" which is placed "on" automatically, that is, in response to a necessary operative movement of a given component of the weapon. As a result, the safety is placed "on" whenever operation of the given component occurs and an intentional act of the shooter is not required. Once the safety is "on" it remains "on" until intentionally released by the shooter.

While automatic safety mechanisms have been available heretofore, they generally comprise a plurality of components, adding excessively to manufacturing costs of weapons so equipped.

The principal object of this invention is to provide an improved automatic safety for bolt action firearms.

Another object of this invention is to provide a safety of the above type of simple and inexpensive construction.

The above and other objects and advantages of this invention will be more readily apparent from the following description and with reference to the accompanying drawings in which:

FIG. 1 is a partial side elevational view of a firearm embodying this invention;

FIG. 2 is a view similar to FIG. 1 with parts in section and in which the safety mechanism is "on";

FIG. 3 is a view similar to FIG. 2 in which the safety is in "off" position;

FIG. 4 is a section taken along line 4—4 of FIG. 2 showing the relationship of the safety and receiver; and

FIG. 5 is a plan view of the safety.

Referring in detail to the drawing, a firearm embodying this invention is shown generally at 10. The firearm is a bolt-action type having a bolt 12 slidably and rotatably disposed within the receiver 14 of the weapon. The operation of the bolt is controlled by an operating handle 16 which extends radially outwardly of the bolt. The bolt handle 16 is rotatable in a plane perpendicular to the axis of the bolt and is rotated upwardly for unlocking and downwardly for locking the bolt in the receiver.

The bolt 12 may be of any conventional type and as shown comprises a striker 18 operated by a coil spring, not shown. The striker includes a lug 20 (FIGS. 2 and 3) which fits into a slot 22 in the receiver. The striker is held in cocked position by engagement of the lug 20 with a sear which forms part of the firing mechanism, shown generally at 26.

Depending from the undesired of the receiver, rearwardly of a bolt operating lever slot 24, is the firing mechanism of the weapon. The firing mechanism comprises a housing member 28 and includes spaced opposed walls 27 and 29 (FIG. 4) for pivotably supporting a trigger 30, sear 32, and safety mechanism 34.

The trigger is pivoted on a pin 36 which is supported by the opposed wall portions of the housing member 28. The trigger includes a sear actuating finger 37 disposed

2

rearwardly of the pivot pin 36 and a notch 38 interengageable with the safety mechanism.

The sear 32 is pivotably supported by a pin 40. As shown, the sear is approximately L-shaped, including a downwardly extending leg 42 engageable by the finger 37 of the trigger. A coil spring 44, extending between the undersurface of the sear and the upper surface of the trigger urges both the sear and the trigger toward their pre-firing positions.

10 In accordance with this invention, the safety mechanism 34 is in the form of a lever preferably of integral spring steel construction. The lever is pivotably mounted on a pin 46 for swinging movement in a plane normal to the plane of movement of the bolt handle 16. The lever comprises a U-shaped portion 51 defined by spaced walls provided with holes which receive the pin 46. This arrangement insures accurate rotation of the safety lever in a given plane. The lower end of the safety comprises latch means interengageable with the trigger. When the safety is engaged with the trigger, the trigger cannot be moved, and consequently inadvertent or unintentional firing of the weapon is not possible.

As shown, the latch means comprises a finger 48 which fits into the correspondingly shaped notch 38 in the trigger. With the safety and trigger in this relative position (FIG. 2), the safety is "on" and the weapon cannot be fired since movement of the firing mechanism is prevented.

The portion of the safety, above the pivot pin 46, is in the form of an arm curved partially around the outer surface of the receiver 14 (FIG. 4). The inner surface of the safety is contiguous to the outer surface of the receiver. A projection or detent 50 extends from the inner surface of the safety into frictional engagement with the outer surface of the receiver. The detent serves to prevent unintentional movement of the safety. If necessary the receiver may be provided with indentations (not shown) positioned to receive the detent 50 to provide positive assurance against inadvertent movement of the safety.

40 The upper portion of the safety also includes a forwardly projecting hook or finger 52 swingable for obstructing the opening of the bolt handle receiving slot 24. The finger 52 serves to actuate the safety in response to bolt operation and to prevent closure of the bolt handle if the safety should be moved "off" while the bolt is open, as shown in the broken line position of FIG. 3.

Lower edge 53 of the finger 52 extends forwardly at an oblique angle relative to the center line of the arm so that rearward pivotal movement of the safety occurs in response to upward movement of the bolt handle 16, as when the bolt is unlocked after firing. Thus, whenever the bolt is so moved, it serves to cam the safety rearwardly to its "on" position, since rearward movement of the safety causes the finger 48 to engage the notch 38 of the trigger. Thus, when the bolt handle is operated to open the chamber of the firearm, the safety is automatically moved to its "on" position. Thereafter, the weapon may be loaded and the bolt closed in normal fashion. The safety remains "on" throughout these operations because 60 of engagement of projection 50 with the receiver 14.

To fire the weapon, the safety must be "off." This is accomplished by moving its upper end forwardly so that the latch finger 48 is swung clear of the trigger and the finger 52 is swung into the path of movement of the bolt handle, so that whenever the bolt is subsequently opened the safety will be moved to its trigger locking position. An operating flange 54 is provided for convenience in manipulating the safety. The upper surface of the flange may be serrated and provided with an indicator arrow to show the direction of movement required to put the safety on.

Applicant's invention provides a highly effective safety

mechanism which is operative to prevent unintentional discharge of a firearm. The safety is actuated automatically in response to operation of the bolt handle. Moreover, before the weapon can be fired, the safety must be moved to its "off" position in which it is disposed to be cammed "on" by opening of the bolt. These desirable results have been achieved by means of a safety mechanism of simple and inexpensive construction which does not add substantially to the manufacturing costs of weapons equipped therewith.

What is claimed is:

1. In combination with a bolt action firearm in which the bolt is locked and unlocked by angular movement of a bolt operating handle, a safety mechanism comprising an integral lever pivotably mounted for swinging movement to and from interlocking engagement with the firing mechanism of said firearm in response to angular movement of said bolt handle, said lever including a portion engageable by said bolt handle whereby said safety is actuated in response to angular movement of said bolt handle.

2. In combination with a bolt action firearm in which the bolt is locked and unlocked by angular movement of a bolt operating handle, a safety mechanism comprising an integral lever pivotably mounted for swinging movement normal to the plane of angular movement of said handle to and from interlocking engagement with the firing mechanism of said firearm, said lever including a portion engageable by said handle for movement of said safety into locking engagement with said firing mechanism in response to unlocking angular movement of said bolt handle.

3. In combination with a bolt action firearm, in which the bolt is locked and unlocked by angular movement of a bolt handle, a safety mechanism of integral construction mounted for pivotable movement normal to the angular movement of said handle to and from interlocking engagement with the firing mechanism of said firearm, said safety mechanism including a portion pivotable to an obstructing position in the path of movement of the bolt handle whereby said bolt cannot be locked if said safety is "off," said safety being placed "on" by pivotal movement of said safety in response to unlocking movement of said bolt handle.

4. In combination with a bolt action firearm in which

10

the bolt is locked and unlocked by angular movement of a bolt operating handle, a safety mechanism for said firearm comprising a lever of integral construction pivotably mounted for swinging movement alongside the receiver of said firearm, said lever including at its lower end latch means interengageable with the firing mechanism of the firearm to prevent movement thereof when the safety is "on," the upper portion of said lever being curved for swinging movement adjacent the outer surface of the receiver, said upper portion including a finger engageable by said bolt handle for actuating said safety in response to angular movement of said bolt handle.

5. In combination with a bolt action firearm in which the bolt is locked and unlocked by angular movement of a bolt operating handle, a safety as set forth in claim 4 in which means is provided for releasably retaining said safety lever in a predetermined position.

15 6. In combination with a bolt action firearm, a safety as set forth in claim 5 in which said latch means is engageable with the trigger of said firing mechanism, said latch means and trigger being provided with cooperating opposed projections and slots.

20 7. In combination with a bolt action firearm in which the bolt is unlocked by angular movement of a bolt operating handle, a safety which is in the form of an integral lever pivotable intermediate its ends normal to the angular movement of said operating lever, said lever having a latch formed adjacent its lower end and swingable to and from interlocking engagement with the mechanism 25 of said firearm, the upper end of said lever including a cam surface disposed in the path of angular movement of said bolt handle when the latch is out of engagement with said firing mechanism to permit firing, said lever being pivoted into locking engagement with said firing mechanism in response to unlocking movement of said bolt handle, and means for releasably holding said lever in a 30 position in which the cam surface is disposed in the path of angular movement of the bolt handle.
